UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL.

Specification forming part of Design No. 6,393, dated February 11, 1873.

To all whom it may concern:

Be it known that I, FREDERICK WINK, of the city and county of Philadelphia, State of Pennsylvania, have invented a Design for a Shawl-Pattern, of which the following is a specification:

My design is fully represented in the accompanying drawing, and consists of three parallel stripes, A, B, and C, each composed of a number of minor parallel stripes, ribs, or bars of different shades or colors, but plain and uniform throughout, as shown. The narrow stripe B has central parallel stripes of alternate black and white, and at each side an edging, *a*, shaded from a black gradually to a white, with white stripes at each side, as shown in the

drawing; and the body *b* of the fabric is of a shade or color which will contrast strikingly with that of the stripes.

Irrespective of the colors employed, I claim—

1. The design for the stripe B, as shown and described.
2. The design for the whole pattern, including the stripes A, B, and C.

In testimony whereof I have signed my name to this specification in the presence of two subscribing witnesses.

FRED. WINK.

Witnesses:

WM. A. STEEL,
HUBERT HOWSON.
